UNITED STATES PATENT OFFICE.

HENRY M. SKINNER, OF ROCKFORD, ILLINOIS, ASSIGNOR OF ONE-HALF TO
ROCKWOOD SAGER, OF SAME PLACE.

ROLLING COLTER.

SPECIFICATION forming part of Letters Patent No. 287,733, dated October 30, 1883.

Application filed June 7, 1883. (No model.)

To all whom it may concern:

Be it known that I, HENRY M. SKINNER, a citizen of the United States, residing in the city of Rockford, in the county of Winnebago 5 and State of Illinois, have invented new and useful Improvements in Rolling Colters, of which the following is a specification.

This invention relates to colters of that class known as the "caster-rolling colter," 10 and the object of this invention is to produce at a small cost a caster-yoke connection of the colter with a bracket-support, to permit a limited oscillatory movement of the colter, and capable of a lateral adjustment relatively 15 with the plow-beam; and it consists of an intermediate double socket, to connect the yoke with the supporting-bracket, which is illustrated in the accompanying drawings, and will be hereinafter more fully described.

20 Figure 1 is an isometrical representation of a colter embodying my invention, and Fig. 2 is a vertical central section of the connection in the plane of the colter-blade.

In the figures is represented a bracket-support 25 prepared from bar material, bent in the form represented, consisting of the vertical arm A and horizontal arm B. The vertical arm A is designed to engage the vertical side of the plow-beam R, to which it is attached, 30 and made adjustable thereon vertically and lengthwise of the beam by means of the usual screw-bolt clamping-staple, C, which embraces the parts. The horizontal arm B is designed to receive a socket of a suitable construction 35 to support the caster-yoke.

At D is represented a socket rectangular in section, fitted to receive the horizontal arm B of the bracket-support, on which it is made adjustable, and is fixed in place thereon when 40 adjusted by means of a key, E, placed within the socket against the edge of the horizontal

arm, which, when driven, will fix the socket securely in place. One end of this socket D is provided with a vertical tubular socket, F, having its axis at a right angle to the axis of 45 the rectangular socket D, and the upper end of this tubular socket, at H, is fitted in clutch form.

At I are represented the two arms of a bifurcated caster-yoke, having a colter, K, of the 50 usual form, mounted to revolve between the arms on a suitable journal-bearing supported in the end of the yoke-arms. The forward end of the caster-yoke, at the junction of the yoke-arms, is provided with a stud-journal, N, rising from its upper side, fitted to enter and oscillate in the vertical socket F, and is held in place by means of a holding-pin, P, passed through its projecting end, in position to engage the clutch portion H of the socket, 55 to limit the oscillatory movements of the colter.

By means of the double socket intermediate portion, in connection with the bracket-support and with the bifurcated caster-yoke, 60 I produce a colter capable of a limited oscillatory movement, and made laterally adjustable to line the colter with the plow.

I claim as my invention—

The combination, with the bracket-support 70 having horizontal arm B, and the caster-yoke having a stud-journal, N, with securing-pin P, of the intermediate rectangular socket, D, having a securing device, and a vertical tubular socket, F, arranged at right angles to the 75 axis of said socket D, and having a clutch, H, at its upper end, substantially as and for the purpose herein shown and described.

HENRY M. SKINNER.
